UNITED STATES PATENT OFFICE

118,205

DESIGN FOR TEXTILE FABRIC

Hugh J. Carragher and Thurston B. Wilson,
Brooklyn, Conn., assignors to Powdrell & Alexander, Inc., Danielson, Conn., a corporation of Massachusetts

Application August 10, 1938, Serial No. 79,226

Term of patent 3½ years

To all whom it may concern:

Be it known that we, Hugh J. Carragher and Thurston B. Wilson, citizens of the United States, residing at Brooklyn, in the county of Windham, State of Connecticut, have invented a certain new, original, and ornamental Design for Textile Fabric, of which the following is a specification, reference being had therein to the accompanying drawing, forming part thereof.

The drawing is a face view of a portion of textile fabric, showing our new design.

We claim:

The ornamental design for textile fabric, substantially as shown.

HUGH J. CARRAGHER.
THURSTON B. WILSON.
